(57) **CLAIM**

The ornamental design for a cradle accessory for a toy figure, as shown and described.

DESCRIPTION

FIG. 1 is a front upper left isometric view of a cradle accessory for a toy figure;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dot-dash boundary line illustrates the boundaries of the claim and demarcates portions of the article that form no part of the claimed design.

The broken line showing of the cradle accessory for toy figure is for the purpose of illustrating portions of the article that form no part of the claimed design.

1 Claim, 7 Drawing Sheets
